FIRE EXTINGUISHING METHOD AND COMPOSITIONS

Paul L. Gomory, Broadmoor, Bethesda, Md., assignor to Phillips Petroleum Company, a corporation of Delaware

Application May 2, 1958, Serial No. 732,522

10 Claims. (Cl. 169—1)

This invention relates to fire fighting methods and compositions. In one aspect it relates to a method for extinguishing the flames from a burning liquid. In another aspect it relates to a novel composition for use in extinguishing fire from the surface of a burning liquid. In another aspect it relates to a composition comprising conventional fire extinguishing foam containing a floatable, solid material.

Conventional foam-type fire extinguishing compositions have been used for many years and are well known in the art. For example, premixed powders comprising an acidic salt and a carbonate salt are mixed with water to produce a gas which, along with water, provides a foam for cooling and smothering the fire. Such salts frequently used include sodium hydrogen sulfate or aluminum sulfate and soda ash, which mixtures, when wetted with water, produce CO₂ as a noncombustible gas. The CO₂ is the noncombustion supporting material while the aqueous portion of the foam cools the heated surface which is being vaporized from the flame heat. Foam stabilizing agents such as saponin, soap, glue, etc., have been used in addition to produce a stable gas-liquid foam.

According to my invention, to the above-mentioned conventional ingredients of fire extinguishing compositions I add a floatable solid material which I find assists greatly in providing a seal between the surface of the hot liquid and the atmosphere. Such solid material assists markedly in cooling the surface to reduce the volatilization of the inflammable liquid.

An object of this invention is to provide an improved foam-type extinguishing composition.

Another object of this invention is to provide a foam-type fire extinguishing composition which is more effective than those now in common use.

Another object of my invention is to provide an effective fire extinguishing composition which is relatively inexpensive and simple to use and which requires little or no additional equipment over that already installed for using conventional compositions.

Still another object of my invention is to provide a composition which is adapted to cool the heated liquid surface more rapidly than conventional compositions, and a method for its use.

Still other objects and advantages will be realized upon reading the following description which, taken with the attached drawing, forms a part of this specification.

In the drawing,

Figure 1 illustrates in diagrammatic form an assembly of apparatus suitable for carrying out the method of this invention.

Figure 2 is a sectional view taken on the line 2—2 of Figure 1.

My invention comprises, specifically, a composition consisting essentially of an aqueous fire fighting foam and a finely divided, floatable, noncombustible, solid material such as popped volcanic ash. My invention, furthermore, includes a composition of a conventional foam producing composition and a finely divided, floatable, noncombustible

material. My invention also includes a method for eliminating or reducing vaporization in case of a fire of volatile constituents from the surface of an inflammable liquid which comprises floating a mixture of an aqueous fire extinguishing foam and finely divided, floatable, noncombustible solid on said surface, a suitable solid in one instance being a popped volcanic ash.

The terms noncombustible and noninflammable as applied to the finely divided, floatable material employed as an ingredient of the herein disclosed fire extinguishing composition are used interchangeably and are considered herein to have mutually similar meanings. These terms as used in this specification and claims are understood to limit the solids only to those which are noncombustible or noninflammable under the conditions of use as disclosed and claimed herein.

My novel composition for producing foam containing a carried solid, which solid is floatable on the surface of a burning liquid, comprises conventionally used solid acidic, and carbonate salts with or without conventional foam stabilizers and a floatable, noncombustible solid material. A suitable solid material for use in this composition is a popped volcanic ash. Hollow spheres of such heat and fire resistant plastic materials as a melamine-formaldehyde resin, a phenol-formaldehyde resin, a furfural-aldehyde-phenol resin, a polytetrafluoroethylene resin, certain chlorinated polyethylene resins, etc., are used in the herein disclosed compositions. Hollow microspheres of glass, and metal and like materials are also used as the floatable materials. The advantages of my novel combination of materials over the conventional foam forming materials alone or over the use of solids alone include better coverage of the flaming surface due to the floating, wet solid, and foam forming a complete blanket on the surface of the liquid with the foam sealing the voids between the solid particles. Solids having a high heat absorptive capacity are preferably selected to assist the water of the foam in absorbing heat from and thereby cooling the surface of the flaming liquid.

Furthermore, the incorporation of such floatable, solid material as popped volcanic ash, when incorporated into the dry acidic salt-carbonate salt mixture, assists in preventing caking of the powder in storage.

In addition to assisting in cooling the surface of a flaming liquid, the herein disclosed solid materials serve to reduce the heat transfer ability of the foam from the flaming vapor to the surface of the liquid. The preferred materials are resistant to heat transfer, partially inherently due to their composition and partially due to their form; therefore, they act effectively as thermal insulators to retard the flow of heat.

Since the floatable, solid materials disclosed herein are more or less inert chemically, the use of foam stabilizing materials is, in some cases, unnecessary. The desirability of a stabilizing material can be determined readily by routine test by one skilled in the art in the possession of this disclosure.

The main requirements of the solid materials which are used according to my invention are that the materials must be noninflammable, must be floatable or be capable of being converted into a floatable form and of being reduced to small size, and, of course, they should be relatively inexpensive. Naturally occurring diatomaceous earth, if floatable, serves well for this purpose.

In the drawing, reference numeral 8 identifies a pipe in which water flows, from a source not shown, to my apparatus for use in producing a fire extinguishing foam. A mixture of solid foam producing chemicals and, for example, popped volcanic ash, are provided in a container 9. The water is passed through an inspirator 9a, which inspirator draws the solid materials from container 9. The water and the solid chemicals react to form the foam

and this foam is passed on through an inspirator 10a which adds a foam stabilizer, if necessary, from a container 10. Foam containing the stabilizer is then passed on through a line 11a, a pipe 22 to one or more tanks, as tank 23, or to other containers which contain flaming liquid. Pipes 17, 18, 19 and 20 represent pipes for passage of this foam to other tanks. Each of these other tanks is, if desired, provided with the same type of foam dispersing apparatus as is tank 23. In tank 23, a manifold pipe 26 communicates by way of a check valve 23a with pipe 21 for passage of foam into the tank. Sprays 25 are strategically placed in the inner and upper portion of the tank for proper distribution of the foam. Figure 2, which is a sectional view taken on the line 2-2 of Figure 1, illustrates a suitable positioning of spray nozzles for ejecting foam into the surface of a liquid 24.

In case of a fire all that is necessary is to pump water through pipe 8 and this water, on passing through inspirator 9a, contacts foam producing chemicals; and the mixture, which will be dissolving foam producing chemicals and foam and floatable, solid materials of this invention, is passed on through inspirator 10a for addition of a foam stabilizer. The entire foam is then passed on through manifold pipe 22 to one or more tanks into which it is desired to spray the foam. Check valve 23a is provided to prevent backflow of fluid when the fire fighting system is not in use and also to prevent backflow of fluid in case of an explosion within the tank 23.

In some instances it is desirable to add the solid floatable material, as an aqueous slurry to the foam prior to its introduction into the tank. In this case a pipe 11 conducts foam with or without a foam stabilizer, under the influence of a pump 13 into a tank 14 which contains an aqueous slurry or suspension of such a solid, floatable material as popped volcanic ash. A motor driven stirrer assembly 27 is provided for maintaining the slurry in a fluid condition so that the slurry is transferable in pipes. Foam which passes through pipe 12 into tank 14 forces slurry through a pipe 14a into a inspirator 16 for mixing slurry with foam prior to passage on through manifold pipe 22 to one or more tanks. In some instances it is not necessary to use the inspirating action of inspirator 16, particularly when sufficient pressure is provided by pump 13. In this case aqueous foam from pump 13 with the valve in pipe 11 closed, is pumped through pipe 12 into tank 14 and foam and slurry leave the tank through a pipe 15 or pipe 15a to manifold pipe 22. However, ordinarily, only a small fraction of the main stream of foam is by-passed through pipe 12, with the valve in pipe 11 being only partially closed, into tank 14 and the main portion of the stream passes on through inspirator 16 with the valve in pipe 14a being closed. If desired, the valve in pipe 14a can be opened somewhat so as to remove slurry from tank 14 by the inspirating action of inspirator 16 in addition to passage of slurry through pipe 15 or pipe 15a from the tank. The pipe 15a is provided for passage of slurry from the bottom of tank 14 to manifold 22.

The following specific examples illustrate dry mixtures of foam producing compositions suitable for use according to my invention. In Example 1 the composition comprises 120 pounds of sodium hydrogen sulfate, 160 pounds of sodium carbonate and 40 pounds of popped volcanic ash. In Example 2, to 120 pounds of sodium hydrogen sulfate and 106 pounds of sodium carbonate are added 50 pounds of popped volcanic ash and 1 pound of saponin as a foam stabilizer.

To each of the above compositions is added water at the rate of about 1 gallon per pound of mixed salts to produce about 1 cubic foot of foam.

The popped volcanic ash, or other floatable, solid material, is added in a ratio from about $\frac{1}{6}$ pound to about $\frac{1}{2}$ pound per pound of mixed salts. While these limits are preferred, in some instances less than $\frac{1}{6}$ pound, and

in other instances more than $\frac{1}{2}$ pound, of floatable, solid material is added to the foam producing materials.

I do not intend to be limited to the above illustrative compositions. Other suitable acidic salts and carbonate salts which are known in the art can very well be used in place of those illustrated herein. The salts, however, are mixed in dry powder form, obviously in molar ratios. The quantity of foam stabilizing material, if used, depends on the compound or compounds used, and amounts to be added are well known in the art since the stabilizers mentioned hereinabove are all well known. Usually from about 0.01 up to 1.0 weight percent, based on the dry weight of the total salt, of such stabilizers, is sufficient. However, depending on the source of water used to produce the foam and on the particular foam forming material, amounts of stabilizers outside of the above-mentioned range are sometimes used.

I do not intend to be limited to the use of a dry mixture foam producing material. Liquid foam formers can also be used, such as an aqueous solution of sodium carbonate and an aqueous solution of a liquid acidic material which, when combined, produce foam. Either or both of these solutions may contain the floatable, solid materials of my invention or the solid materials can be added to the foam after it has been produced by combining the two liquids.

A method of converting volcanic ash to cellular particles, or the so called popped volcanic ash, is described in U.S. Patent 2,637,702 of May 5, 1953.

The solid material as used herein should be relatively small in size, for example, such as that which passes a 1-millimeter sieve. However, when employing such materials as popped volcanic ash or diatomaceous earth, these materials must not be so small as not to include buoyant pore space because one of the main points of the invention is that the solid material must be floatable upon the liquid for effective fire extinguishing. Hollow glass, metal or noncombustible resin balls are sometimes larger in outside diameter than the above mentioned 1 millimeter size. They must, however, be sufficiently small as to be handled easily by an inspirator, to flow with foam in pipes, to be sprayed through a suitable spray nozzle, etc., without appreciable breakage or deformation.

As will be evident to those skilled in the art, various modifications of this invention can be made, or followed, in the light of this foregoing disclosure and discussion, without departing from the spirit or scope thereof. While certain embodiments of the invention have been described for illustrative purposes, the invention obviously is not limited thereto.

I claim:

1. A method for reducing contact between the surface of a body of a vaporizable liquid and the surrounding atmosphere comprising the steps of forming a mixture of a fire extinguishing foam and a finely divided, non-combustible solid material, said mixture being floatable on said liquid, and applying said mixture to said surface.
2. A method for eliminating vaporization of a vaporizable constituent from the surface of a body of liquid comprising the steps of forming a mixture of an aqueous fire extinguishing foam and a finely divided, non-combustible solid material, said foam and said material being floatable on said liquid, and floating said mixture on said surface.
3. A method for eliminating combustion conditions on the surface of a body of vaporizable liquid comprising spreading a layer of a composition comprising a fire extinguishing foam and a finely divided, floatable, non-combustible solid material, said composition being floatable on said liquid.
4. A composition suitable for reducing contact between the surface of a body of vaporizable liquid and the surrounding atmosphere, said composition consisting essentially of a fire extinguishing foam and a finely divided,

non-combustible solid material, said composition being floatable on said liquid.

5. The method of claim 1 wherein said material is popped volcanic ash.

6. The method of claim 1 wherein said material is 5 small, hollow glass balls.

7. The method of claim 1 wherein said solid is hollow metal balls.

8. The method of claim 2 wherein said solid is popped volcanic ash. 10

9. The method of claim 3 wherein said material is popped volcanic ash.

10. The composition of claim 4 wherein said solid is popped volcanic ash.
